UNITED STATES PATENT OFFICE.

MOSES MIGDALOWITZ, OF ROCHESTER, NEW YORK, ASSIGNOR OF ONE-THIRD TO
NATHAN SINGER AND ONE-THIRD TO PHILIP ROSEN, BOTH OF ROCHESTER, NEW
YORK.

DOUBLE POCKET AND MEANS FOR LOCKING SAME.

Application filed March 13, 1924. Serial No. 698,882.

To all whom it may concern:

Be it known that I, MOSES MIGDALOWITZ, a citizen of the United States, residing at Rochester, in the county of Monroe and State of New York, have invented certain new and useful Improvements in Double Pockets and Means for Locking Same, of which the following is a specification.

The object of this invention is to provide trousers, coats or other garments with double pockets and means whereby these pockets can be locked so that money or other valuable articles may be carried therein without risk of having it accidentally lost or 15 stolen by pickpockets.

These and other objects of this invention will be fully illustrated in the drawing, described in the specification and pointed out in the claims at the end thereof.

20 In the accompanying drawing:

Figure 1 is a perspective view of a portion of a pair of trousers provided with the double pocket and the means for locking it.

Figure 2 is a vertical sectional view of the 25 pocket.

In the figures of the drawing, like reference numerals indicate like parts.

The double pocket forming the subject matter of this invention is adapted for trousers, coats and other garments in which 30 the pockets are provided on the outside where they are easily accessible. Articles or money carried in the outer pockets of trousers, coats, etc., are always carried at the 35 risk of losing them by accident, or by having them picked by pickpockets, unless some means are provided whereby the pocket or pockets can be locked.

Double pockets are desirable because it 40 makes it possible to carry money in one-half and other articles in the other half of the pocket so that the contents of one half of the pocket cannot get mixed up with the contents of the other half.

45 The double pocket in combination with the locking means therefor is illustrated in the figures of the drawing. The pocket is made up in the form of the ordinary single pocket except that a partition 2 is sewed into the pocket that divides the single pocket into two compartments 3 and 4.

50 The front of this partition is faced with a strip of goods matching the material of

the trousers or has such a strip attached thereto and in this strip are provided two 55 button holes 5 and 6. Buttons 7 and 8 are located on the inside of the pocket, one on each side of the partition 2 and opposite to the button holes provided therein. These 60 buttons are placed on the inside of the pocket so that they divide the length of the pocket into approximately three sections. When, therefore, the buttons are buttoned to the partition 2 from each side of the 65 pocket the large openings leading into each of the pockets are reduced to a point where a hand can no longer be inserted into the pockets. In buttoning up each button the opening of the pocket which it closes is reduced in size approximately one third which 70 is enough to prevent the insertion of the hand into this particular pocket. The other pocket is closed in the same way with a button located on the opposite side. Either one or the other or both of the pockets can thus 75 be locked with the two buttons.

A double pocket made up in accordance with this invention is thus in appearance identical to a single pocket in that it is not necessary to add much material to a single 80 pocket to make it into the double pocket. By providing two buttons to the pocket and two button holes in the partition in the manner above described and illustrated in the drawing the two halves of the pocket are 85 locked without providing bulky means that would make the pocket protrude from the trousers as is now the case with pockets having locking means provided thereon.

90 I claim:

1. A double pocket and means for locking same comprising two exterior walls, a partition located between said exterior walls, a button on the inside of each of said exterior walls, one of said buttons being located about one third of the length of the opening of the pocket from one end thereof and the other button being located an equal distance from the other end of the opening of the pocket, said partition having a pair of button holes provided therein located opposite to the buttons provided on the inside of said exterior walls, said partition being adapted to be buttoned to each of said exterior walls with one of said buttons to reduce the opening leading into each half of 100 105

the double pocket whereby both pockets at the same time or either pocket may be locked independently of the other pocket.

2. In a double pocket, the combination of two outer walls, a partition between said outer walls having two button holes provided therein, a button on the inside of each of said outer walls and opposite to one of

the button holes provided in said partition, said partition being adapted to be partly 10 buttoned to one of said outer walls and partly to the other of said outer walls to partially close each of the pockets of said double pockets.

In testimony whereof I affix my signature.
MOSES MIGDALOWITZ.
